[57] **CLAIM**

The ornamental design for an auxiliary device for a punch, as shown and described.

DESCRIPTION

FIG. 1 is a top plan view of auxiliary device for a punch embodying our new design;

FIG. 2 is a front elevational view thereof;

FIG. 3 is a left side elevational view thereof;

FIG. 4 is a right side elevational view thereof;

FIG. 5 is a bottom view thereof;

FIG. 6 is a perspective view with the pivoted arm in a raised position; and,

FIG. 7 is a perspective view with the pivoted arm in a lowered position.

The punch and sheet of paper depicted by means of broken lines in FIGS. 6 and 7 have been shown for illustrative purposes only and form no part of the claimed design.
